(57) **CLAIM**

The ornamental design for an applicator, as shown and described.

DESCRIPTION

FIG. 1 is a perspective view of the first embodiment of my new ornamental design for an applicator. The body of the applicator is round and the rear and side views are identical to the view in FIG. 1.

FIG. 2 is a top view thereof.

FIG. 3 is a bottom view thereof.

FIG. 4 is a perspective view of the second embodiment of my new ornamental design for an applicator.

FIG. 5 is a top view of the embodiment shown in FIG. 4; and,

FIG. 6 is a bottom view of the embodiment shown in FIGS. 4 and 5.

The broken lines showing a bottle in FIGS. 1 and 4 are for illustrative purposes only and do not form part of the claimed design.
